SOUND REPRODUCING APPARATUS

Harold A. Wheeler, Great Neck, and William O. Swinyard, Bayside, N. Y., assignors to Hazeltine Corporation, a corporation of Delaware

Application April 10, 1935, Serial No. 15,546

13 Claims. (Cl. 181—31)

This invention relates to sound-reproducing apparatus. The invention is particularly concerned with such apparatus as is now generally used in connection with radio broadcast receivers and which includes a sound reproducer of the type having a cone or diaphragm of relatively large area.

In attempting to provide a uniformly effective distribution of reproduced sound waves, throughout a room or auditorium where the reproducing apparatus is employed, and to avoid so-called "directional effects", distortions, and interference patterns, certain difficulties are met with due to the nature of certain parts of the reproducing apparatus employed and to certain peculiarities of behavior of the sound waves radiated by reproducers of the type mentioned.

More particularly, while the employment of a sound cavity in connection with a reproducer of the type mentioned, through which cavity the sound waves are radiated, has certain desirable effects, including the proper loading of the reproducer diaphragm and the amplification of the sound waves, such cavities as have heretofore been employed have caused certain objectionable so-called "directional effects" which have impaired the uniformity of distribution of the radiated sound waves. These results have been occasioned by the angular positions of the sound cavity walls, resulting in such a propagation of the waves as to fail to provide effective reception at certain locations, particularly locations to the side of the apparatus.

Furthermore, it is well known that sound reproducers of the type having a cone or diaphragm of relatively large area, while in many ways being admirably adapted to the use in question, tend to radiate the sound waves of higher frequencies substantially as a beam, while the lower frequency waves are radiated substantially spherically, thus resulting in a predomination of the sounds of higher pitch in regions directly in front of the reproducer and a predomination of the sounds of lower pitch in adjacent regions.

It is also well known that, where a sound cavity of the type before described is employed, the presence of parallel surfaces and edges within or adjacent to the cavity causes, respectively, undesirable refractions and reflections, which in turn result in the setting up of interference patterns and a non-uniform effectiveness of the reproduction of the various sound waves throughout the range of audible frequencies, due to the tendency of waves which are so reflected or refracted as to arrive simultaneously at the same location to

either neutralize or reinforce each other, thereby impairing the fidelity of reproduction at different locations.

An object of the present invention is to provide an improved high-fidelity sound-reproducing apparatus whereby sounds will be reproduced and propagated with uniform effectiveness and fidelity throughout the entire region forward of the reproducer in a room or auditorium in connection with which the apparatus is employed.

A further object is to provide an apparatus of the character aforescribed, characterized by simplicity and sturdiness while being symmetrical and so proportioned as to present an artistic appearance.

Other and further objects of and advantages achieved by this invention will be apparent from the following description of a preferred embodiment thereof which is illustrated in the accompanying drawing.

In accordance with the present invention, there is provided an improved sound cavity having an especially wide spread or angular divergence so as to effectively radiate sound waves radiated by a reproducer employed in connection therewith, throughout the entire region forward of the apparatus in a room where the same is employed. A deflector is employed in connection with the cavity, so arranged as to effect a diffusion of the higher frequency waves which would otherwise tend to be propagated as a beam in the undesirable aforescribed manner. The various surfaces provided by the cavity walls and deflector walls within the cavity are so arranged as not only to provide the aforementioned desirable effects, but also to have no parallel surfaces or edges and to thereby avoid the undesirable reflection and refraction effects aforesaid.

The various other features comprised in this invention will be apparent from the detailed description hereinafter set forth.

In the accompanying drawing, Fig. 1 is a perspective view of a radio receiver embodying the sound-reproducing apparatus of this invention; Fig. 2 is an enlarged front elevation showing the apparatus of the invention separately; Fig. 3 is a vertical section on the line III—III of Fig. 2; and Fig. 4 is a horizontal section on the line IV—IV of Fig. 2.

Referring in detail to the drawing, the receiver illustrated therein, which embodies the present preferred form of the invention, comprises a cabinet indicated generally by the numeral 10. In the upper portion of the cabinet a radio receiving apparatus (not shown) is housed in the conven-

tional manner. The front of the cabinet below the portion housing the receiving apparatus is open and the side walls 11 of the cabinet at this portion are of reduced width.

- 5 A sound cavity, indicated generally by the numeral 12, and separately shown in Figs. 2, 3 and 4, is constructed in the portion of the cabinet below the receiving apparatus. The cavity 12 is of conical, pyramidal or polyhedral form, truncated by the front and side walls of the cavity (the cavity in the embodiment illustrated, for example, being of rectangular-pyramidal form). The axis of the cavity is horizontal, with the apex thereof behind the cavity. The cavity is characterized by a very wide angle of divergence at its horizontal center plane, as hereinbefore more fully described.

The wall structure defining the sound cavity is secured to the walls of the cabinet by suitable means (not shown). Vertical brace members or posts 13 are provided at each corner of the cabinet and may, if desired, extend the entire height thereof.

25 An opening 14 is provided in the wall structure of the sound cavity, preferably in the lower portion 15 thereof, which portion slants so as to face in a direction slightly above the horizontal. A sound reproducer 16 is disposed behind the cavity opposite the opening. The reproducer is of the 30 type having a cone or diaphragm of relatively large area, the forward edge of its diaphragm being suitably engaged around the margin of the opening, with the axis of the diaphragm disposed perpendicularly to the plane of the opening, and 35 in accordance with the foregoing description is inclined forwardly and slightly upwardly.

A deflector, indicated generally by the numeral 17, is provided within the sound cavity. The deflector is also of conical, pyramidal or polyhedral form (as, for example, in the embodiment illustrated, the deflector is of rhombic-pyramidal form). The axis and apex of the deflector are coincident with the axis and apex, respectively, of the sound cavity. The angle of divergence of the 45 deflector at its horizontal center plane is substantially less than the angle of divergence of the cavity at this plane, while at the vertical plane of symmetry of the cavity the deflector is preferably tangent therewith, the lower tangent portion of the deflector extending across the opening 14. The "base" of the deflector terminates in the plane of the front of the cabinet, and 50 may be either open or closed.

55 Two vertical brace members or posts 18 are provided, one at each side of the deflector, at the front of the cabinet, and may, if desired, extend the entire height thereof. The sides of the deflector are suitably secured to the respective posts 18.

60 The deflector thus divides the cavity into two passageways at its opposite sides, and by virtue of the relative angular arrangement of the cavity and deflector walls no parallel surfaces or edges are provided thereby.

65 In the operation of the apparatus audio-frequency or sound waves are radiated by the diaphragm of the sound reproducer 16 through the opening 14, into and through the sound cavity. The relative angular arrangement of the walls of

70 the sound cavity provides a divergence which approaches an angle of 180 degrees (in the embodiment illustrated approximately 150 degrees) in the horizontal center plane and a divergence at an angle of approximately 120 degrees in the vertical center plane, and the lateral spread there-

by provided is of such magnitude as to effect a substantially uniform distribution of the radiated sound waves throughout the entire region forward of the apparatus in a chamber where the apparatus is employed. The amounts of divergence may, of course, be varied within limits from the above-mentioned amounts provided in the approved embodiment described, while still providing the desired results.

Further, it will, of course, be understood that the invention is not limited to specific shapes as to the cavity and the deflector, except insofar as the angularities of divergence necessary to provide the uniform distribution and diffusion of the sound waves, in the manner hereinbefore set forth, are concerned. It will be understood that in the appended claims the word "conical" is used in its general sense, and it is intended to include all of the various so-called conical or pyramidal forms as well as all suitable polyhedral or curved forms.

The entire inner surface of the sound cavity serves, in effect, as a baffle, but the main baffling effect is, of course, provided by the portion 15 of the cavity wall structure, which slants at an angle 25 of approximately 30 degrees to the vertical, the axis of the sound reproducer being, as afore-described, perpendicular to the surface of this wall. By virtue of this slanting arrangement of the wall 15 and the position of the diaphragm, 30 there results a propagation of the sound waves in a direction slightly above the horizontal, that is to say, in the general direction of the heads of listeners in a chamber of average size into which the sound waves are radiated. Upon coming in 35 contact with the diverging slanting surfaces of the deflector, the sound waves of relatively high frequencies, which would otherwise tend to be propagated substantially as a beam, will be deflected and diffused throughout the area forward 40 of the apparatus so as to provide a substantially uniform distribution thereof, as with the low-frequency waves. There being no parallel surfaces or opposite edges provided by the cavity and deflector walls, the sound reproduction will 45 be free from distortion, interference patterns and other undesirable effects usually caused by such reflections and refractions.

The arrangement and construction of the reproducing apparatus, as aforedescribed, presents 50 a structure which is characterized not only by sturdiness and simplicity but also by symmetry and artistic appearance. Where desired, however, a screen of loosely woven fabric may be provided across either the deflector opening, the 55 cavity openings, or both, in the conventional manner, to protect the apparatus in the cavity.

While an approved embodiment of the apparatus of the present invention has been hereinbefore described, it will be readily apparent that 60 many and various changes and modifications in form, structure and arrangement of the parts may be made without departing from the spirit of the invention, and it will be understood that all and any such changes and modifications are 65 contemplated as a part of this invention, as defined in the appended claims.

What is claimed is:

1. A high-fidelity sound-reproducing apparatus comprising wall structure defining a sound cavity of conical form with its axis substantially horizontal; a sound reproducer adapted to radiate sound waves into and through said cavity; and a deflector of conical form disposed in said cavity in the path of said sound waves having 75

- its axis and apex coincident with the axis and apex of said cavity, the angle of divergence of said deflector being substantially less than the angle of divergence of said cavity in at least one plane through the axis of said cavity.
2. A high-fidelity sound-reproducing apparatus comprising wall structure defining a sound cavity of conical form with its axis substantially horizontal, said cavity diverging in the horizontal center plane through the axis of said cavity at an angle approaching 180 degrees; a sound reproducer adapted to radiate sound waves into and through said cavity; and a deflector of conical form disposed in said cavity in the path of said sound waves, having its axis and apex coincident with the axis and apex of said cavity, the angle of divergence of said deflector being substantially less than the angle of divergence of said cavity in said horizontal center plane.
3. A high-fidelity sound-reproducing apparatus comprising wall structure defining a sound cavity of conical form with its axis substantially horizontal; a sound reproducer adapted to radiate sound waves into and through said cavity; and a deflector of conical form disposed within said cavity in the path of said sound waves, and having its axis and apex coincident with the axis and apex of said cavity, the edges of said deflector being tangent with the wall structure of said cavity in one plane through the axis of said cavity, and the angle of divergence of said deflector being less than the angle of divergence of said cavity in a plane through the axis of said cavity perpendicular to the first said plane.
4. A high-fidelity sound-reproducing apparatus comprising wall structure defining a sound cavity of conical form with its axis substantially horizontal; a sound reproducer adapted to radiate sound waves into and through said cavity; and a deflector of conical form disposed within said cavity in the path of said sound waves, and having its axis and apex coincident with the axis and apex of said cavity, the edges of said deflector being tangent with the wall structure of said cavity in a vertical plane through the axis of said cavity, and the angle of divergence of said deflector being less than the angle of divergence of said cavity in the horizontal plane through the axis of said cavity.
5. A high-fidelity sound-reproducing apparatus comprising wall structure defining a sound cavity of conical form with its axis substantially horizontal; a sound reproducer of the relatively large area cone or diaphragm type adapted to radiate sound waves into and through said cavity; and a deflector of conical form disposed in said cavity in the path of said sound waves having its axis and apex coincident with the axis and apex of said cavity, the angle of divergence of said deflector being substantially less than the angle of divergence of said cavity in the horizontal plane through the axis of said cavity, said deflector being adapted to diffuse sound waves tending to be radiated through said cavity substantially as a beam, the angle of divergence of said cavity in said horizontal plane through the axis of said cavity approaching 180 degrees, so as to effect together with the diffusion of said deflector, uniform distribution of said sound waves substantially throughout the entire region forward of said apparatus in a chamber into which said sound waves are radiated.
6. A high-fidelity sound-reproducing apparatus comprising wall structure defining a sound cavity of conical form having its axis substantially horizontal; and a sound reproducer adapted to radiate sound waves into and through said cavity, the angle of divergence of said cavity in the horizontal plane through the axis of said cavity approaching 180 degrees to thereby effect substantially uniform distribution of said sound waves throughout the entire region forward of said apparatus in a chamber into which said sound waves are radiated and the angle of divergence of said cavity in the vertical plane through the axis of said cavity being substantially less than said angle of divergence in said horizontal plane.
7. A high-fidelity sound-reproducing apparatus comprising wall structure defining a sound cavity of conical form having its axis substantially horizontal, said cavity thereby including a lower wall structure portion facing in an upward direction and said portion having an opening formed therein; and a sound reproducer disposed behind said lower portion with its axis substantially perpendicular thereto and adapted to radiate sound waves through said opening, and into and through said cavity, the angle of divergence of said cavity wall structure in the horizontal plane through the axis of said cavity approaching 180 degrees, to effect thereby substantially uniform distribution of said sound waves throughout the entire region forward of said apparatus in a chamber into which sound waves are radiated.
8. A high-fidelity sound-reproducing apparatus comprising wall structure defining a sound cavity of conical form having its axis substantially horizontal; a sound reproducer adapted to radiate sound waves into and through said cavity; and a deflector disposed within said cavity across the path of said waves adapted to diffuse sound waves tending to be radiated from said reproducer as a beam, the angle of divergence of said cavity in the horizontal plane through the axis of said cavity approaching 180 degrees to effect thereby substantially uniform distribution of said sound waves throughout the entire region forward of said apparatus in a chamber into which said sound waves are radiated and the angle of divergence of said cavity in the vertical plane through the axis of said cavity being substantially less than said angle of divergence in said horizontal plane.
9. A high-fidelity sound-reproducing apparatus comprising wall structure defining a cavity of polyhedral form with its axis substantially horizontal; a sound reproducer adapted to radiate sound waves into and through said cavity; and a deflector of polyhedral form disposed in said cavity in the path of said sound waves having its axis and apex coincident with the axis and apex of said cavity, the angle of divergence of said deflector being less than the angle of divergence of said cavity in at least one plane through the axis of said cavity.
10. A high-fidelity sound-reproducing apparatus comprising wall structure defining a cavity of tetrahedral form with its axis substantially horizontal; a sound reproducer adapted to radiate sound waves into and through said cavity; and a deflector of polyhedral form disposed in said cavity in the path of said sound waves having its axis and apex coincident with the axis and apex of said cavity, the angle of divergence of said deflector being less than the angle of divergence of said cavity in at least one plane through the axis of said cavity.
11. A high-fidelity sound-reproducing appa-

5 ratus comprising wall structure defining a cavity of polyhedral form with its axis substantially horizontal; a sound reproducer adapted to radiate sound waves into and through said cavity; and a deflector of tetrahedral form disposed in said cavity in the path of said sound waves having its axis and apex coincident with the axis and apex of said cavity, the angle of divergence of said deflector being less than the angle of divergence of said cavity in at least one plane through the axis of said cavity.

10 12. A sound-reproducing apparatus symmetrical with respect to a vertical plane, comprising a conical baffle having an opening in its lower side, a cone-diaphragm sound radiator mounted behind said baffle to subtend, and to radiate through, said opening, and a conical deflector, said baffle and deflector diverging toward the front of said apparatus and having a common 15 apex and horizontal axis in said vertical plane, said deflector being tangent to said baffle only in said plane, and said baffle having in any other

plane through said axis a greater angle of divergence than said deflector.

13. A sound-reproducing apparatus symmetrical with respect to a vertical plane, comprising a rectangular-pyramidal baffle having an opening in its lower side, a cone-diaphragm sound radiator mounted behind said baffle to subtend, and to radiate through, said opening, and a rhombic-pyramidal deflector, said baffle and deflector diverging toward the front of the apparatus and having a common apex and horizontal axis in said plane, said baffle having between its vertical sides a dihedral angle of nearly 180 degrees and between its upper and lower sides a lesser angle exceeding 90 degrees, and said deflector having between its upper and lower edges an angle equal to said lesser angle and between its other edges a still lesser angle on the order of 90 degrees. 10 15
